(57) CLAIM

I claim the ornamental design for a ice cream scoop, as shown and described.

DESCRIPTION

FIG. 1 is a side view of the ice cream scoop showing my design; an opposite side view being a mirror image thereof.

FIG. 2 is a bottom view thereof;

FIG. 3 is a top plan view thereof;

FIG. 4 a rotated front view thereof;

FIG. 5 is a rotated back view thereof; and,

FIG. 6 is a perspective view thereof.
